(57) CLAIM

The ornamental design for a tee shirt with a micro-fiber liner, as shown and described.

DESCRIPTION

FIG. 1 is a front perspective view of a tee shirt with a micro-fiber liner, showing my new design;

FIG. 2 is a front elevation view thereof;

FIG. 3 is a rear elevation view thereof;

FIG. 4 is a left side view thereof;

FIG. 5 is a right-side view thereof;

FIG. 6 is a top plan view thereof;

FIG. 7 is a bottom plan view thereof; and,

FIG. 8 is a sectional view taken along lines 8-8 of FIG. 2 illustrating the micro-fiber liner in the interior of the tee shirt.

The trademark material containing the word “Sweat” on the front and on the rear of the tee shirt, and the sweat drops with the word “Sweat” on the rear of the tee shirt are owned by the inventor and are not registered trademarks.

1 Claim, 6 Drawing Sheets
